UNITED STATES PATENT OFFICE.

ROSS WILLIAM SATTLER, OF MOUNT VERNON, OHIO.

ROUNDABOUT.

1,093,591.

Specification of Letters Patent. Patented Apr. 14, 1914.

Application filed June 14, 1911. Serial No. 633,089.

To all whom it may concern:

Be it known that I, Ross WILLIAM SATTLER, a citizen of the United States, residing at Mount Vernon, in the county of Knox and State of Ohio, have invented certain new and useful Improvements in Roundabouts, of which the following is a specification, reference being had to the accompanying drawings.

10 My invention relates to new and useful improvements in amusement apparatus and more particularly to a roundabout, and my object is to provide a device of this character which may be propelled by the occupants 15 of the respective seats thereof.

A further object of the invention resides in providing an improved means of propulsion for the movable objects, comprising substantial friction clutches which act upon the 20 wheels of the movable devices.

Still another object of the invention resides in providing a device which is extremely simple and economical in construction, thereby readily and cheaply manufactured, and one which is very useful and effective in operation.

With these and other objects in view, my invention consists in the novel features of construction, combination and arrangement 30 of parts as will be hereinafter referred to and more particularly pointed out in the specification and claims.

In the accompanying drawings forming a part of this application, Figure 1 is a fragmentary top plan view of the device showing portions of one of the movable objects removed. Fig. 2 is a side elevation thereof. Fig. 3 is an enlarged section as seen on line 3—3, Fig. 1. Fig. 4 is a similar view as 40 seen on line 4—4, Fig. 1. Fig. 5 is a side elevation of the hub or base in which the central mast is mounted, and, Fig. 6 is a section through the track as seen on line 6—6, Fig. 2.

45 In carrying out my invention, I shall refer to the drawings in which similar reference characters designate corresponding parts throughout the several views and in which—

50 1 indicates a mast or center pole carried on a hub or the like 2, said hub being braced and secured in the center of a circular track 3 by means of a plurality of brace wires or rods 4. This circular track 3 is substantially 55 inverted T-shape in cross section and the wires or rods 4 are engaged with the hub

by passing the inner ends thereof through openings in said hub, while the outer ends of said wires are threaded, as shown at 5, and passed through openings in the extensions of said T-shaped track, said threaded ends being engaged by the nuts 6, whereby the same are securely held in position.

Revolutionly mounted on the central mast 1, is a frame or the like comprising a hub having a plurality of radially extending arms 7, said arms being secured, respectively, to a plurality of movable objects which are adapted to rotate on the circular track 3. These movable objects may be termed cars 70 or the like and comprise the upper and lower platforms 8 and 9, respectively, said lower platform in each instance being secured to the upper platform by means of the brace or suspension arms 10 and has secured thereto, the outer end of a radial arm 7. The platforms of said cars are designed arcuately, the curvature thereof being substantially coincident to the curvature of the track 3, and said platforms are additionally 80 braced to the radial arms 7 by means of the brace rods 11.

Carried adjacent to each end of the lower platform, is a pair of bearings 12, which bearings are spaced apart and have rotatably mounted therebetween, the axles 13 and 14, and carried, respectively, on said axle, are the wheels 15 and 16 which are adapted to rest on the upper faces of the track 3 and rotate thereon. These wheels 90 are each provided with a collar or the like 17 on one face of the hub thereof through which extends a screw 18 which is adapted to engage the axle and cause the same to rotate with the rotation of said wheel, and 95 each of said wheels is also provided with an annular rim flange 19 which is adapted to engage the inner face of the extension of the T-shaped track to prevent the wheels from displacement therefrom.

100 The wheel 15 which is mounted on the axle 13, has the face of the hub thereof opposite that carrying the collar 17, enlarged and provided with an annular flange 20, thereby forming a circular recess or the like between 105 the axle and the inner wall of said flange, and loosely mounted on said axle 13, is a crank or the like 21, the lower or pivotal end of which is enlarged to form a head 22, said head being increased in thickness and of a 110 size substantially equal to the size of the recess inclosed by the flange 20, which recess

is adapted to receive the same. The inner face of the head 22 is provided with a cam slot 23 in which is disposed to freely move therein, the circular lug or clutch member 24, whereby it will be seen that when said crank is partially rotated, the clutch member 24 will bind against the end wall 25 of said slot and against the inner periphery of the annular flange 20, thereby causing the 10 wheel 15 to be rotated. It will be seen, however, that the rotation of the wheel will release the binding of the lug 24 between the walls, as just described, thereby not affecting the crank 21. In order to cause this wheel 15 to be operated by the occupant of the car, a lever 26 is provided on each car which extends through a slot 27 in the upper platform thereof and is pivotally mounted in a bearing 28 therebelow, the upper end of said 20 lever being provided with a handle 29 and the lower end thereof pivotally engaged with one end of a linking member 30, the opposite end of said linking member being similarly engaged with the upper end of the 25 crank 21. The crank 21 is held in position on the axle 13 by means of a collar 31, whereby the enlarged head 22 thereof is normally disposed within the space inclosed by the annular flange 20, and it will be seen 30 that when it is desired to propel the car, it is only necessary for the occupant thereof to pull upon the handle 29, which will indirectly cause the crank 21 to be partially rotated. The partial rotation of the crank 21, 35 as stated before, will cause the lug 24 to frictionally bind between the inner periphery of the annular flange 20 and the end wall 25 of the cam slot, thereby forcing the wheel 15 into rotation.

40 Each one of the movable objects or cars, as they may be termed, may be provided with a similar arrangement for the propulsion of the same or only certain cars may be equipped with the same, as desired, and in 45 any instance, it will be seen that the cars will be readily adapted to rotate on the track with the operation of the lever 26 by the occupants thereof.

From the foregoing, it will be seen that I 50 have provided a roundabout which is adapted to be propelled by the occupants thereof,

and it will further be seen that I have provided an improved means for the propulsion of the respective cars. It will still further be seen that this friction arrangement which 55 is provided on each of the cars for propelling the same, performs the function of a clutch which is manually operated, and it will further be seen that while the lever will cause the rotation of the wheel when forced 60 in one direction, there will be absolutely no possibility of the clutch binding during such rotation of said wheel. Furthermore, it will be seen that my device is of such simple construction as to be readily and cheaply 65 manufactured, and one which is very effective and useful in operation.

What I claim is:—

1. In a structure of the class described, the combination with a central vertical mast, 70 of a car member comprising a main platform, a pair of bars disposed in spaced relation beneath the platform, standards connecting said bars and platform, a shaft pivoted to the mast and extending radially 75 therefrom and secured to the intermediate portions of the bars, straps secured to the end portions of the bars and directed inwardly and secured to the shaft, and wheeled axles carried by the end portions of 80 said bars.

2. In a roundabout, the combination with a circular track of inverted T-shape design, a mast mounted centrally thereof, a substantial hub supporting the lower end of said 85 mast and having upper and lower annular flanges thereon, said flanges being provided with a plurality of openings, bracing wires engaged at their inner ends with the openings in said flanges, the outer ends of said 90 wires being threaded and disposed through the vertical portion of the inverted T-shape track, and nuts engaging the threaded ends of said wires to secure the same in position; of a truck mounted on the track, and means 95 to support said truck from the mast.

In testimony whereof I hereunto affix my signature in the presence of two witnesses.

ROSS WILLIAM SATTLER.
